DESIGN FOR A CANISTER

George W. Stallings, Jackson, Mich., assignor to A. Kreamer, Incorporated, New York, N. Y., a corporation of New York

Application November 25, 1936, Serial No. 66,139

Term of patent 14 years

To all whom it may concern:

Be it known that I, George W. Stallings, a citizen of the United States and a resident of Jackson, in the county of Jackson and State of Michigan, have invented a new, original, and ornamental Design for a Canister, of which the following is a specification, reference being had to the accompanying drawing, forming part thereof.

I claim:

The ornamental design for a canister, as shown.

GEORGE W. STALLINGS.
